Arlington, Va. 22205

Filed Feb. 10, 1971, Ser. No. 114,405

Term of patent 14 years

Int. Cl. D21—01

U.S. Cl. D34—5

FIG. 1 is a perspective view of my new gameboard design; and

FIG. 2 is a staggered cross section illustrating a unitary construction.

The characteristic feature of my design resides in the central truncated cone having a plurality of apertures for receiving play implements in combination with the similarly apertured board as shown.

I claim:

The ornamental design for a gameboard, substantially as shown and described.
